UNITED STATES PATENT OFFICE.

PHILLIP KRAKAUER, OF BROOKLYN, NEW YORK.

SPRING-CUSHION STRUCTURE.

Application filed November 26, 1926. Serial No. 150,649.

This invention relates to spring cushions of the well known type in which the springs are housed within individual cells or pockets and maintained in the proper position in the cushion structure by the fabric walls of the cells or pockets. This invention also contemplates the provision of an improved method of constructing such cushions.

In order that cushions of the type referred to may be adapted for practical manufacture economically in large quantities, certain requirements must be met, as follows. First, the cushion should use a minimum amount of material. This I have accomplished by the provision of a single layer of fabric between springs at all points and throughout the cushion surfaces, and by the use of partition walls which form cells open at the corners. Second, the cushion should be adapted for construction with the minimum amount of labor not only in assembling and stitching the parts of the cushion in place but also in filling the cells or pockets with springs. I have attained this end by adapting the cushion for assembly by means of a series of continuous lines of stitching each going completely across the cushion and by the provision of obstructions at certain corners of the cells which make it impossible for the tool used to fill a row of cells with springs to enter the wrong row. Third, there should be a thickness of fabric arranged between the springs at all points so as to minimize the possibility of noise caused by the springs rubbing against each other or by colliding when the cushion is depressed. Finally, the structure must be such that the cushion is well adapted for quantity production.

I have met all of the above requirements by the cushion structure and the method involved in this invention, the various objects of which will appear as this description progresses.

Referring to the accompanying drawings forming a part hereof,

Fig. 1 is a top view, partly in horizontal section, of my improved cushion showing particularly the arrangement of the various walls or partitions.

Fig. 2 is a vertical section of the same taken on the line 2—2 of Fig. 1.

Figs. 3 and 4 are perspective views of my improved cushion with some of the parts deleted to show the steps in seaming the

upper ends of the partitions to the top of the casing.

Fig. 5 is a perspective view of one of the cell forming elements bent into the shape which it assumes in the completed cushion, 60 and Fig. 6 is a perspective view of the uncompleted cushion, showing the partitions seamed to the bottom. In this view, the partitions are represented as standing upright though it will be understood that since 65 said partitions are preferably made of fabric, they will naturally tend to collapse flat.

The outer casing 10 may be made of a single piece of material as illustrated or said casing may be made of two halves of the 70 same size seamed together along the free edges in a manner which is well known and need not here be described in detail.

The interior of the cushion is divided up into a series of substantially square cells or 75 pockets 11 arranged in rows, parallel to the edges and sides of the cushion. For convenience I will call the rows between the sides 15 and 16 of the cushion longitudinal rows, and those between the edges 17 and 18 80 of the cushion, transverse rows. To form the cells or pockets 11 I use three different types of partitions or pocket forming elements. One type of said partitions consists of the narrow strips 12, each having a vertical wall 21, of less width than that of the cell, and end portions 22 and 23. The second type of said partitions consists of strips 85 13 each substantially twice as wide as the strips 12, and formed into the shape of an L 90 in horizontal section, so that each strip 13 forms two adjacent perpendicular walls of a cell. The strip 13 has a longitudinal wall 24 with end portions 25 and 26 and a transverse wall 27 having end portions 28 and 29. 95 The third type consists of the wide strips 14 arranged across the cushion from one side 100 to the other side as 16, and having a continuous wall 30 forming a longitudinal wall of each cell in certain longitudinal rows and end portions 31 and 32. The upper and lower ends of each of said partitions are respectively secured to the top 19 of the casing 10 and to the bottom 20 of said casing.

For so securing the partitions 12, 13 and 14 in position, I prefer to turn the upper end portions 22, 25, 28 and 31 and the lower end portions 23, 26, 29 and 32 thereof at right angles to the vertical walls 21, 24, 27 and 30 respectively thereof and to stitch said upper 110

and lower end portions respectively to the top and bottom of the casing as will be more fully described hereinafter.

In securing said end portions in place in the casing, the end portions of the longitudinal walls 24 and 30 are all turned toward the cushion edge 17 while the end portions of the transverse walls 21 and 27 are turned toward the side 16 so that continuous lines of seaming as straight as possible may be used in the attachment thereof to the casing. After the end portions of the partitions have been stitched into position, the casing itself is seamed on the side 16 and the edge 17 so as to close said casing all around except on one side as 15 thereof. The side 15 is left open so that a suitable tool containing enough springs to fill an entire longitudinal row of cells in one operation, may be inserted through said open side. To fill the first row, the tool is inserted through the open side as 15, and pressed into contact with the wall of the edge 17, so that said tool can slide between the edges of the strips 12 and the edge 17 of the cushion into the proper row. Similarly, to fill the second longitudinal row, the tool is pressed against the wall 30 and slides into the proper row between the edges of the walls 27 and the wall 30. It will be seen that the six rows of cells illustrated may be rapidly filled from the open side after which the casing is closed on that side in the usual manner. By reason of the fact that I make use of the wide strips 14, it becomes advisable to leave either the side 15 or the side 16 open for the purpose of inserting springs into the cushions.

The cells 11 formed by the peculiar arrangement of the partitions shown and described are of two different types. One type of cell of which the strip 12 forms a part is open at all of the four corners thereof, while the other type of which the strip 13 forms a part is open at only three of the corners and closed at the fourth by means of the bend 33 formed at the corresponding corners of all of the strips 13.

In the final position of the various elements of the cushion a pair of long continuous strips 14 are arranged parallel to each other and are spaced apart a distance equal to the width of two cells. The strips 14 extend across the cushion from the side 15 to the side 16 or parallel to the edges 17 and 18 of the casing and parallel to the continuous bend between the top and bottom of the casing in that case where a casing of a single piece of fabric is used. On one side of each of the said strips 14, is arranged a series of narrow strips 12 in parallel relation and substantially perpendicular to the strip 14, each of said strips having the upright edge of the wall 21 thereof spaced from the strip 14 and each

being of less width than the width of the cell. On the other side of the strip 14, I prefer to arrange the L-shaped strips or angles 13, one wall 27 of each of which is arranged in alignment with the wall 21 of the adjacent strip 12 and the other wall 24 of which is arranged perpendicular to the wall 27.

It will be seen that by this arrangement I provide one-piece continuous walls in alternate rows throughout the cushion and that a double row of cells is formed by the use in adjacent rows of a set of narrow strips 12 and a set of L-shaped strips 13 on each side of the wide strips 14. By means of this construction it becomes possible to utilize a minimum number of wide strips with a comparatively large number of small strips of two different sizes so that material left over from cutting the casing and the wide strip 14 may be used for the smaller strips without detracting from the efficiency of the cushion.

In the formation of my improved cushion, I provide a casing 10 cut to size and marked on the inner faces of the top and bottom thereof with longitudinal lines as 34 and transverse lines as 35 dividing the said faces into a series of squares of the desired number of rows. I also provide strips 12, and strips 13, the latter having slits as 36 extending a considerable distance inwardly toward each other from the ends thereof, said distance being greater than the width of the end portions 25 and 26 and I provide further the wide strips 14. The sewing machine operator first seams into place the strips adapted to form the transversely arranged walls of the cells, beginning preferably though not necessarily at the edge 17. That is, the operator starts at the edge 17 of the casing, arranges the edge portion 23 of a narrow strip 12 on the line 35 and starts a seam across from the edge 17 transversely of the cushion toward the edge 18. After seaming the first strip 12 in place, the operator arranges the edge portion 26 of the strip 13 on the lines 35, continuing the seam across said edge portion. A short strip 12 comes next and then a longer strip 13 and so on across the cushion, the strips 12 and 13 alternating along the line, and sufficient space being left between them to allow the insertion therebetween of the strips 14. In the same manner, the stitching is made along the next line 35 and the remaining transverse lines of the cushion, until all of the transverse parallel stitching has been completed.

The operator then may start at the side 15 or 16 of the casing, and after first seaming a short strip 12 into place as above described along the line 34, arranges the edge portions 26 of the strips 13 along the line 34 in succession as the stitching reaches said

edge portions and completes the stitching. The next longitudinal line of stitching secures the edge portion 32 of the wide strip 14 in place. These operations are repeated 5 throughout the remaining longitudinal lines until the stitching to the bottom 20 has been completed.

In seaming the upper end portions of the partitions to the top 19 of the casing, a 10 somewhat different procedure is followed. This is necessitated by reason of the fact that a sewing machine seam cannot be run continuously across an obstruction without ending the seam on one side and starting a 15 new seam on the other side of the obstruction. Continuous straight-line seams both longitudinally and transversely of the casing cannot therefore be made on both faces of the casing. Continuous seams not in 20 straight lines however, are used to secure the transversely arranged end portions 22 and 28 of the strips 12 and 13 in place, and straight-line seams are used on the longitudinally arranged end portions 25 and 31.

Where a one-piece casing is used, having a continuous web at the edge 18 thereof, the stitching on the top 19 is preferably started near said edge, either on the transverse line 35 nearest the side 16 or that nearest the 25 side 15 of the casing. The upper end portion 28 of the strip 13 nearest the edge 18 and the side 15 is first seamed in place by a straight seam 38 of about the width of a cell on the line 35 the straight seam reaching just past the end portion of the first strip 13 just described. The line of stitching however is not broken but the cushion is freed in the machine so that the stitching may be continued along a diagonal line as 35, which as viewed in Fig. 1 reaches from the left hand end of the first seam to the right hand end of the short straight seam required on the succeeding line 35 for the 40 next strip 13 in the row. All of the end portions 28 in the row of cells nearest the side 18 are thus seamed in place by a single zig-zag line of stitching as 37. From the last strip 13 the stitching is continued longitudinally toward the side 16, thereby securing the end portion of the longitudinal strip 12 nearest the side 16 in position along the longitudinal line 34 nearest the edge 18.

The cushion structure is then turned so that the line of stitching may be continued 55 by the operator in a straight longitudinal line 39 along the marked line 35 as indicated in Fig. 4, whereby the end portions 25 of the strips 13 are seamed into position. When the end of the line 35 nearest the side 15 is 60 reached, the cushion is again turned so that a short longitudinal line of stitching 40 may be run back along the line 35 to the first line 34. The zig-zag stitching securing the end portions 22 of the strips 12 in place in 65 the next row is repeated in the manner above

described in connection with the first row to be seamed to the top of the casing. The zig-zag stitching 37 and the straight line stitching 39 is alternated in this manner until the upper end portions of all the strips 70 have been secured to the top 19 of the casing.

The side 16, the edge 17, and if necessary the edge 18 are closed by seaming the free edges of the casing 10 together at said sides and edges 16, 17 and 18 whereby the cushion 75 is left open at the side 15 only. The longitudinal rows of cells may then be filled with springs in the manner hereinbefore described by means of a suitable tool, and finally the casing may then be closed at the 80 side 15.

It will be seen that I have provided a cushion well adapted for economical manufacture in large quantities and a method for constructing such a cushion which meet 85 the requirements hereinbefore set forth. It will further be seen that various changes may be made both in the construction of the cushion and in the method of making the same which are contemplated, but which 90 need not be set forth herein in detail, since said changes will be obvious and fall within the purview and the range of equivalents afforded by the appended claims.

I claim:

1. In a spring cushion having a plurality of spring holding cells, a wide partition extending longitudinally across said cushion, a series of L-shaped strips each having two walls, one of which is parallel to and the other perpendicular to said wide partition, said strips being arranged in a row across said cushion on one side of said wide partition with the said parallel walls thereof in longitudinal alignment, and a series of transversely arranged narrow strips forming walls arranged parallel to each other and perpendicular to and on the other side of said wide partition.

2. In a spring cushion, a fabric casing, a vertical fabric partition arranged longitudinally across said cushion, a row of parallel vertical fabric strips arranged transversely on one side of said partition, a row of vertical L-shaped fabric strips all facing the 110 same way on the other side of said partition whereby access to all of the cells of the cushion in any longitudinal row may be had from one side thereof, and horizontal end portions on said partition and strips at the 115 top and bottom thereof seamed respectively to the top and bottom of the casing and all directed toward either one of two of the adjacent sides of said cushion.

3. The process of making a spring cushion comprising marking the inner faces of the top and bottom of a casing with lines dividing said faces into squares, sewing the bottom edge of a narrow strip and of half of a wider strip alternately in position along 120 125 130

one of said lines on the bottom by a single straight continuous line of stitching transversely of the cushion, repeating the last mentioned step for the remaining transverse lines of the bottom of the casing, bending the wider strips into L-shape so that the bottom edges are on the longitudinal marked lines, seaming said last mentioned bottom edges on said longitudinal lines by straight continuous lines of stitching, seaming the bottom edge of a wide partition to the casing bottom by a straight continuous line of stitching between the free edges of the L-shaped strips and the narrow strips, reversing the partly seamed cushion, seaming the upper edges of half of each of the last L-shaped strips in the line nearest one edge of the cushion to the respective transverse lines on the top of the casing by zig-zag lines of stitching, seaming the other half of the last mentioned strips to a longitudinal line by a straight continuous line of stitching, and repeating the zig-zag and longitudinal stitching, until all of the upper edges of the partition members have been seamed to the casing top, the seaming being progressive toward the strips nearest the other side of the cushion.

4. The process of making a spring cushion consisting of marking the casing of the cushion on the inner faces of the top and bottom thereof, into squares by means of longitudinal and transverse lines indicating the place where the partitions are to be seamed, seaming one end of each of a series

of narrow partition strips and half of each of a series of wider partition strips in alternate arrangement on the transverse lines of the casing bottom, seaming a single partition across the cushion between the wider strips and the narrow strips, seaming the other half of the wider strips to the casing bottom along longitudinal lines, and seaming the upper ends of the partitions to the casing top by a continuous series of zig-zag and straight lines of stitching alternately, closing all but one side of the cushion, filling each longitudinal row of cells thus formed with springs simultaneously through the open side, and closing the side of the cushion through which the springs have been inserted.

5. The process of making a spring cushion consisting of seaming a series of narrow partition strips and seaming half of each of a series of partition strips about twice as wide as said narrow strips in alternate relation to the bottom of a casing by means of continuous straight lines of stitching, bending the wider strips into L-shape, seaming the other half of each of said wider strips to the casing bottom by continuous straight lines of stitching, seaming strips of the width of the cushion between said wider and said narrow strips, and seaming the free upper ends of said strips to the casing top by alternating zig-zag and straight lines of stitching.

PHILLIP KRAKAUER.
